LAMP STANDARD

James H. Boye, Chicago, Ill.

Application January 19, 1933. Serial No. 652,512

12 Claims. (Cl. 240—81)

This invention relates to the art of electric floor lamps, and has reference more particularly to a new and improved standard or stem structure for such lamps.

5 Electric floor lamps commonly comprise three main parts,—a base in the form of a broad heavy casting to afford stability, a standard or stem comprising a section of gas pipe for the passage of the cord, sheathed in and concealed by ornamental spindle sections and breaks strung thereon, and a cluster head mounted on the upper end of the standard and carrying a cluster of lights.

10 Heretofore, so far as I am aware, in the manufacture of the standard the spindle members of the sheathing or covering have comprised sections of sheet metal tubing of somewhat larger internal diameter than the external diameter of the cord conductor pipe, and the so-called "breaks" have consisted of hollow castings with 15 openings in their ends also of somewhat larger diameter than the conductor pipe for the free passage of the latter therethrough. Usually shallow cup-shaped seating washers are interposed between the meeting ends of the spindle 20 sections and the breaks.

25 In the manufacture of the break castings, which is usually performed by what is known as the "slush mold" method (a method wherein the molten metal is poured into the upper or "run" 30 end of the mold and allowed to harden on the internal walls of the mold, and the surplus is then poured out through the "run" end by inverting the mold), the end walls of the casting are 35 rough and rarely lie in planes normal or at right angles to the axis of the casting. In other words, they are more or less slanting to the axis. Then, too, the ends of the spindle sections are sometimes cut not perfectly normal to their axes but 40 slightly slanting. The result is, that when the spindle sections and breaks are tightened endwise by nuts on the ends of the conductor pipe, a lateral slip occurs between the spindle sections 45 or their seating washers and the breaks, throwing them out of true alignment, and making a ram-shackle and unsightly job. Furthermore, under 50 the above described conditions, when the clamping pressure is applied, the compression is not distributed uniformly throughout the walls of the thin sheet metal spindle sections, with the 55 result that they will spring, bow or crack to a greater or less extent, since they are not internally braced against the central conductor pipe. This, too, gives the standard a crooked and ugly

In some instances, by employing in the lower end of the mold a plug with a suitably formed face, one end wall of the casting has been shaped with a seat to receive the engaging end of a spindle section; but it is impossible to cast such a seat 60 in the other or "run" end of the mold, so that lateral displacement readily occurs between the "run" end of the casting and the engaging end of a spindle section.

The principal object of the present invention is 65 to produce a lamp standard structure of the general character above outlined which will be entirely free from the faults and defects above enumerated, and in which the elements of the covering or sheathing will always be maintained rigidly 70 in perfect axial alignment and straight throughout. This object is mainly accomplished according to my present invention, through the provision of a hollow break casting having rigid 75 with both ends thereof spindle seating members so formed as to hold the ends of spindles engaged therewith against lateral displacement relatively thereto and formed with holes adapted to have a sliding fit on a cord tube; and, in the preferred 80 form of the invention, through the additional use of braces within the spindle sections themselves which serve to prevent lateral displacement or bending, bowing or cracking of the latter relatively 85 to the cord tube.

85 Referring to the accompanying drawing, in which I have illustrated one practical embodiment of the invention,

Fig. 1 is a vertical axial section through the lamp standard broken off at its ends, embodying 90 my present improvements.

Fig. 2 is an enlarged vertical section through one of the cast metal breaks and adjacent portions of the spindle sections engaged therewith.

Fig. 3 is a horizontal section on the line 3—3 of 95 Fig. 2, looking in the direction indicated by the arrows.

Fig. 4 is an isolated perspective detail of a spindle seating cap that is rigidly secured in one end of the break casting during and by the molding 100 operation.

Referring to the drawing, 10 designates a central cord conductor pipe, usually a section of gas pipe, forming the main strength-giving element of the standard. This pipe is an element common 105 to practically all lamp standards of the type to which the present invention relates. The pipe is sheathed and concealed by an ornamental covering comprising, in the present instance, alternating tubular spindle sections 11 and hollow 110

white metal castings 12 commonly known in the trade as "breaks".

These break castings are usually made by the "slush mold" method hereinabove briefly outlined. 5 In the casting operation as practiced prior to my present invention, the lower end of the mold is closed by an inserted plug which forms a bottom wall of the mold and, of course, affords a bottom wall to the casting. After the metal has been 10 poured and allowed to stand long enough to form a hardened shell on the internal walls of the mold, the latter is inverted, and the balance of the molten metal flows out through the upper open or "run" end of the mold and the filling funnel, 15 leaving a sprue which is cut off. This leaves a hole in the upper end wall of the casting, and a hole is then cut in the bottom wall of the casting, these holes being for the passage of the pipe 10. As heretofore made, the holes in the end walls 20 are more or less irregular lop-sided, and eccentric, and have no true sliding fit on the pipe 10.

In making the break casting of my invention, I first form a pressed sheet metal spindle seating and centering member or cap which is best 25 shown in isolated detail in Fig. 4 and is designated as an entirety by 13. In the preferred form of this cap, the same has an outer up-standing marginal flange 14 that forms the outer wall of a spindle seating groove or channel 15, a central upstanding tapered and shouldered protuberance or boss 16 that forms the inner wall of the groove or channel 15, and a transversely rounded and convex annular extension 17 of the boss 16 that constitutes the margin of a central 30 hole or mouth 18 that is of a size to have a sliding fit on the pipe 10. The upper outwardly flaring portion of this annular extension 17 forms a lip or flange 19 that is gripped between suitable holding members on the mating sections of 40 the mold during the molding operation.

Before pouring the metal into the mold, the opposite end of the latter is closed by a plug having on its face a concave annular groove or countersink which forms in the end wall of 45 the casting a convex or tapered annular boss 20, and between the latter and the peripheral wall of said end a seating groove or channel 21 similar to the groove 15 of cap 13 for the end of a spindle section 11. The portion of the end wall surrounded by the boss 20 is removed to form a hole 22 of the same size as, and registering with, the mouth 18 of the pressed metal cap 13.

In the molding operation the metal flows not only around the peripheral flange 14 of the cap 55 13, but also over the under surface of the boss 16, as clearly shown in Fig. 2, whereby the cap 13 is rigidly embedded and locked within the run end of the casting. I have found that by giving to the wall 17 of the mouth 18 the transversely convex and flaring form shown and described, the metal that is flowed out through the mouth 18 comes clean and without leaving a sprue on the mouth, which otherwise would require removal for the passage of the pipe 10. 60 The outer marginal wall 14 of the cap, which is embedded in the end of the casting has the further useful function of reinforcing and strengthening said end, and the downwardly tapered side of the boss 16 serves to guide and center the end of the spindle section in the groove 15, the outer tapered side of the boss 20 performing the same function at the other end 70 of the casting.

It will readily be seen that the above described 75 construction of spindle seats not only accurately

centers the spindle sections 11 relatively to the ends of the break castings, but prevents any relative lateral displacement of the spindle sections and breaks, when they are clamped endwise on the rod 10, and maintains the integrity, solidity 80 and uniform appearance of the assembled sectional sheathing.

With a view to obviating any bending or bowing of the spindle sections themselves under the end clamping pressure, I preferably employ in 85 connection with each spindle section one or more intermediate braces which may take the form of metal caps 23, that have a snug sliding fit in the spindle sections and the transverse walls of which are apertured to have a similar fit on 90 the pipe 10. Manifestly, these brace members 23 also cooperate with the caps 13 and the bottom end walls of the break castings in maintaining the axial coincidence of the pipe and its sheathing throughout the full length of the standard, 95 and providing a strong and rugged structure in the handling of the lamp.

I claim:

1. As an element of a floor lamp standard, a 100 hollow casting having rigidly mounted in an end thereof a sheet metal spindle seating member so formed as to hold the end of a spindle section engaged therewith against lateral displacement relatively thereto.

2. As an element of a floor lamp standard, a 105 hollow casting having rigidly mounted in an end thereof a sheet metal spindle seating member formed with an annular groove in its outer face adapted to engage with the end of a spindle section and support the latter against lateral displacement relatively to said casting.

3. As an element of a floor lamp standard, a 110 hollow casting having embedded and locked in an end thereof a sheet metal spindle seating member formed with a central apertured boss and an annular groove in its outer face encircling said boss and adapted to engage with the end of a spindle section.

4. As an element of a floor lamp standard, a 115 hollow casting having embedded and locked in an end thereof a sheet metal spindle seating member formed with a tapered apertured spindle-centering boss and an annular groove in its outer face encircling said boss and adapted to engage with 120 the end of a spindle section.

5. As an element of a floor lamp standard, a 125 hollow slush mold casting having rigidly mounted in the run end thereof a pressed metal spindle seating member so formed as to hold the end of a 130 spindle section engaged therewith against lateral displacement relatively thereto.

6. As an element of a floor lamp standard, a 135 hollow slush mold casting having embedded in the run end thereof a pressed metal spindle seating member formed with an annular groove in its outer face adapted to engage with the end of a spindle section and support the latter against lateral displacement relatively to said casting.

7. As an element of a floor lamp standard, a 140 hollow casting having rigid with the ends thereof rigid spindle seating members so formed as to hold the ends of spindle sections engaged therewith against lateral displacement relatively 145 thereto, said seating members formed with holes adapted to have a sliding fit on a cord tube.

8. As an element of a floor lamp standard, a 150 hollow slush mold casting having at one end thereof an integral wall formed with an annular groove in its outer face adapted to engage with

the end of a spindle section and having embedded in the run end thereof a pressed metal seating member formed in its outer face with an annular groove adapted to similarly engage with the end 5 of a spindle section.

9. As an element of a floor lamp standard, a hollow casting having rigidly mounted in an end thereof a pressed metal spindle seating member formed with an annular groove in its outer side 10 to engage with the end of a spindle section and support the latter against lateral displacement relatively to said casting, the outer edge of said member being substantially flush with the end of said casting, whereby to strengthen the walls of 15 the latter at said end.

10. As an element of a floor lamp standard, a hollow slush mold casting having rigidly mounted in the run end thereof a pressed metal cap formed with an annular groove to seat and center a spindle section and with a central hole formed with a 20 transversely rounded convex bounding wall.

11. As an element of a floor lamp standard, a hollow slush mold casting having embedded and locked in the run end thereof a pressed metal cap formed with an annular groove to seat and center a spindle section and with a central hole formed with a transversely rounded convex bounding wall terminating in an outwardly flaring lip or flange. 80

12. A floor lamp standard, comprising, in combination, a central cord conductor pipe, a plurality of tubular sheet metal spindle sections and cast metal breaks strung end to end in alternating relation on said pipe and forming a sheathing for the latter, said spindle sections and breaks being of greater internal diameter than the external diameter of said pipe, annular braces between 85 said spindle sections and said pipe, and annular braces rigid with the ends of said breaks and having a sliding fit on said pipe. 90
